(57) **CLAIM**

The ornamental design for a case for electronic device, as shown and described.

DESCRIPTION

FIG. 1 is a front perspective view of a case for electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is a open perspective view thereof; and,

FIG. 9 is an open rear perspective view thereof.

Features shown in broken lines in FIGS. 1, 2, 3, 4, 5, 6, 7, 8, and 9 form no part of the claimed design. The dot-dash lines show an unclaimed boundary.

1 Claim, 7 Drawing Sheets(56)
